(57) **CLAIM**

The ornamental design for a battery for electric pallet jack, as shown and described.

DESCRIPTION

FIG. 1 is a perspective environmental view illustrating a battery for electric pallet jack installed in a pallet jack, in accordance with the present invention;

FIG. 2 is a perspective view of the battery for electric pallet jack of FIG. 1;

FIG. 3 is a front view of the battery for electric pallet jack of FIGS. 1 and 2;

FIG. 4 is a back view of the battery for electric pallet jack of FIGS. 1-3;

FIG. 5 is a first side view of the battery for electric pallet jack of FIGS. 1-4;

FIG. 6 is a second opposite side view of the battery for electric pallet jack of FIGS. 1-5;

FIG. 7 is a top view of the battery for electric pallet jack of FIGS. 1-6; and,

FIG. 8 is a bottom view of the battery for electric pallet jack of FIGS. 1-7.

The broken lines in the Figures are for the purpose of illustrating environmental structure and portions of the battery for electric pallet jack that form no part of the claimed design.

1 Claim, 7 Drawing Sheets
